CLAIM

The ornamental design for a T-handle lock, as shown and described.

DESCRIPTION

FIG. 1 is a three dimensional view looking at the top, front left corner;

FIG. 2 is a top plan view;

FIG. 3 is a right side elevation view and the left side is an exact mirror image of the right side; and,

FIG. 4 is an end elevational view the ends being exact mirror images of one another.

No ornamental feature is present on the bottom of the enclosure and accordingly it is not shown herein.

The broken lines are for illustrative purposes only and form no part of the claimed design.
